<img alt="Technical drawings of a bridge structure, labeled Fig. 2 and Fig. 1. Fig. 2 shows a longitudinal view of a bridge deck with various components labeled with numbers 6, 19, 79, 101, 106, 119, 125, 137, 144, 148, 149, 151, 155, 157, 159, 161, 163, 165, 167, 169, 171, 173, 175, 177, 179, 181, 183, 185, 187, 189, 191, 193, 195, 197, 199, 201, 203, 205, 207, 209, 211, 213, 215, 217, 219, 221, 223, 225, 227, 229, 231, 233, 235, 237, 239, 241, 243, 245, 247, 249, 251, 253, 255, 257, 259, 261, 263, 265, 267, 269, 271, 273, 275, 277, 279, 281, 283, 285, 287, 289, 291, 293, 295, 297, 299, 301, 303, 305, 307, 309, 311, 313, 315, 317, 319, 321, 323, 325, 327, 329, 331, 333, 335, 337, 339, 341, 343, 345, 347, 349, 351, 353, 355, 357, 359, 361, 363, 365, 367, 369, 371, 373, 375, 377, 379, 381, 383, 385, 387, 389, 391, 393, 395, 397, 399, 401, 403, 405, 407, 409, 411, 413, 415, 417, 419, 421, 423, 425, 427, 429, 431, 433, 435, 437, 439, 441, 443, 445, 447, 449, 451, 453, 455, 457, 459, 461, 463, 465, 467, 469, 471, 473, 475, 477, 479, 481, 483, 485, 487, 489, 491, 493, 495, 497, 499, 501, 503, 505, 507, 509, 511, 513, 515, 517, 519, 521, 523, 525, 527, 529, 531, 533, 535, 537, 539, 541, 543, 545, 547, 549, 551, 553, 555, 557, 559, 561, 563, 565, 567, 569, 571, 573, 575, 577, 579, 581, 583, 585, 587, 589, 591, 593, 595, 597, 599, 601, 603, 605, 607, 609, 611, 613, 615, 617, 619, 621, 623, 625, 627, 629, 631, 633, 635, 637, 639, 641, 643, 645, 647, 649, 651, 653, 655, 657, 659, 661, 663, 665, 667, 669, 671, 673, 675, 677, 679, 681, 683, 685, 687, 689, 691, 693, 695, 697, 699, 701, 703, 705, 707, 709, 711, 713, 715, 717, 719, 721, 723, 725, 727, 729, 731, 733, 735, 737, 739, 741, 743, 745, 747, 749, 751, 753, 755, 757, 759, 761, 763, 765, 767, 769, 771, 773, 775, 777, 779, 781, 783, 785, 787, 789, 791, 793, 795, 797, 799, 801, 803, 805, 807, 809, 811, 813, 815, 817, 819, 821, 823, 825, 827, 829, 831, 833, 835, 837, 839, 841, 843, 845, 847, 849, 851, 853, 855, 857, 859, 861, 863, 865, 867, 869, 871, 873, 875, 877, 879, 881, 883, 885, 887, 889, 891, 893, 895, 897, 899, 901, 903, 905, 907, 909, 911, 913, 915, 917, 919, 921, 923, 925, 927, 929, 931, 933, 935, 937, 939, 941, 943, 945, 947, 949, 951, 953, 955, 957, 959, 961, 963, 965, 967, 969, 971, 973, 975, 977, 979, 981, 983, 985, 987, 989, 991, 993, 995, 997, 999, 1001, 1003, 1005, 1007, 1009, 1011, 1013, 1015, 1017, 1019, 1021, 1023, 1025, 1027, 1029, 1031, 1033, 1035, 1037, 1039, 1041, 1043, 1045, 1047, 1049, 1051, 1053, 1055, 1057, 1059, 1061, 1063, 1065, 1067, 1069, 1071, 1073, 1075, 1077, 1079, 1081, 1083, 1085, 1087, 1089, 1091, 1093, 1095, 1097, 1099, 1101, 1103, 1105, 1107, 1109, 1111, 1113, 1115, 1117, 1119, 1121, 1123, 1125, 1127, 1129, 1131, 1133, 1135, 1137, 1139, 1141, 1143, 1145, 1147, 1149, 1151, 1153, 1155, 1157, 1159, 1161, 1163, 1165, 1167, 1169, 1171, 1173, 1175, 1177, 1179, 1181, 1183, 1185, 1187, 1189, 1191, 1193, 1195, 1197, 1199, 1201, 1203, 1205, 1207, 1209, 1211, 1213, 1215, 1217, 1219, 1221, 1223, 1225, 1227, 1229, 1231, 1233, 1235, 1237, 1239, 1241, 1243, 1245, 1247, 1249, 1251, 1253, 1255, 1257, 1259, 1261, 1263, 1265, 1267, 1269, 1271, 1273, 1275, 1277, 1279, 1281, 1283, 1285, 1287, 1289, 1291, 1293, 1295, 1297, 1299, 1301, 1303, 1305, 1307, 1309, 1311, 1313, 1315, 1317, 1319, 1321, 1323, 1325, 1327, 1329, 1331, 1333, 1335, 1337, 1339, 1341, 1343, 1345, 1347, 1349, 1351, 1353, 1355, 1357, 1359, 1361, 1363, 1365, 1367, 1369, 1371, 1373, 1375, 1377, 1379, 1381, 1383, 1385, 1387, 1389, 1391, 1393, 1395, 1397, 1399, 1401, 1403, 1405, 1407, 1409, 1411, 1413, 1415, 1417, 1419, 1421, 1423, 1425, 1427, 1429, 1431, 1433, 1435, 1437, 1439, 1441, 1443, 1445, 1447, 1449, 1451, 1453, 1455, 1457, 1459, 1461, 1463, 1465, 1467, 1469, 1471, 1473, 1475, 1477, 1479, 1481, 1483, 1485, 1487, 1489, 1491, 1493, 1495, 1497, 1499, 1501, 1503, 1505, 1507, 1509, 1511, 1513, 1515, 1517, 1519, 1521, 1523, 1525, 1527, 1529, 1531, 1533, 1535, 1537, 1539, 1541, 1543, 1545, 1547, 1549, 1551, 1553, 1555, 1557, 1559, 1561, 1563, 1565, 1567, 1569, 1571, 1573, 1575, 1577, 1579, 1581, 1583, 1585, 1587, 1589, 1591, 1593, 1595, 1597, 1599, 1601, 1603, 1605, 1607, 1609, 1611, 1613, 1615, 1617, 1619, 1621, 1623, 1625, 1627, 1629, 1631, 1633, 1635, 1637, 1639, 1641, 1643, 1645, 1647, 1649, 1651, 1653, 1655, 1657, 1659, 1661, 1663, 1665, 1667, 1669, 1671, 1673, 1675, 1677, 1679, 1681, 1683, 1685, 1687, 1689, 1691, 1693, 1695, 1697, 1699, 1701, 1703, 1705, 1707, 1709, 1711, 1713, 1715, 1717, 1719, 1721, 1723, 1725, 1727, 1729, 1731, 1733, 1735, 1737, 1739, 1741, 1743, 1745, 1747, 1749, 1751, 1753, 1755, 1757, 1759, 1761, 1763, 1765, 1767, 1769, 1771, 1773, 1775, 1777, 1779, 1781, 1783, 1785, 1787, 1789, 1791, 1793, 1795, 1797, 1799, 1801, 1803, 1805, 1807, 1809, 1811, 1813, 1815, 1817, 1819, 1821, 1823, 1825, 1827, 1829, 1831, 1833, 1835, 1837, 1839, 1841, 1843, 1845, 1847, 1849, 1851, 1853, 1855, 1857, 1859, 1861, 1863, 1865, 1867, 1869, 1871, 1873, 1875, 1877, 1879, 1881, 1883, 1885, 1887, 1889, 1891, 1893, 1895, 1897, 1899, 1901, 1903, 1905, 1907, 1909, 1911, 1913, 1915, 1917, 1919, 1921, 1923, 1925, 1927, 1929, 1931, 1933, 1935, 1937, 1939, 1941, 1943, 1945, 1947, 1949, 1951, 1953, 1955, 1957, 1959, 1961, 1963, 1965, 1967, 1969, 1971, 1973, 1975, 1977, 1979, 1981, 1983, 1985, 1987, 1989, 1991, 1993, 1995, 1997, 1999, 2001, 2003, 2005, 2007, 2009, 2011, 2013, 2015, 2017, 2019, 2021, 2023, 2025, 2027, 2029, 2031, 2033, 2035, 2037, 2039, 2041, 2043, 2045, 2047, 2049, 2051, 2053, 2055, 2057, 2059, 2061, 2063, 2065, 2067, 2069, 2071, 2073, 2075, 2077, 2079, 2081, 2083, 2085, 2087, 2089, 2091, 2093, 2095, 2097, 2099, 2101, 2103, 2105, 2107, 2109, 2111, 2113, 2115, 2117, 2119, 2121, 2123, 2125, 2127, 2129, 2131, 2133, 2135, 2137, 2139, 2141, 2143, 2145, 2147, 2149, 2151, 2153, 2155, 2157, 2159, 2161, 2163, 2165, 2167, 2169, 2171, 2173, 2175, 2177, 2179, 2181, 2183, 2185, 2187, 2189, 2191, 2193, 2195, 2197, 2199, 2201, 2203, 2205, 2207, 2209, 2211, 2213, 2215, 2217, 2219, 2221, 2223, 2225, 2227, 2229, 2231, 2233, 2235, 2237, 2239, 2241, 2243, 2245, 2247, 2249, 2251, 2253, 2255, 2257, 2259, 2261, 2263, 2265, 2267, 2269, 2271, 2273, 2275, 2277, 2279, 2281, 2283, 2285, 2287, 2289, 2291, 2293, 2295, 2297, 2299, 2301, 2303, 2305, 2307, 2309, 2311, 2313, 2315, 2317, 2319, 2321, 2323, 2325, 2327, 2329, 2331, 2333, 2335, 2337, 2339, 2341, 2343, 2345, 2347, 2349, 2351, 2353, 2355, 2357, 2359, 2361, 2363, 2365, 2367, 2369, 2371, 2373, 2375, 2377, 2379, 2381, 2383, 2385, 2387, 2389, 2391, 2393, 2395, 2397, 2399, 2401, 2403, 2405, 2407, 2409, 2411, 2413, 2415, 2417, 2419, 2421, 2423, 2425, 2427, 2429, 2431, 2433, 2435, 2437, 2439, 2441, 2443, 2445, 2447, 2449, 2451, 2453, 2455, 2457, 2459, 2461, 2463, 2465, 2467, 2469, 2471, 2473, 2475, 2477, 2479, 2481, 2483, 2485, 2487, 2489, 2491, 2493, 2495, 2497, 2499, 2501, 2503, 2505, 2507, 2509, 2511, 2513, 2515, 2517, 2519, 2521, 2523, 2525, 2527, 2529, 2531, 2533, 2535, 2537, 2539, 2541, 2543, 2545, 2547, 2549, 2551, 2553, 2555, 2557, 2559, 2561, 2563, 2565, 2567, 2569, 2571, 2573, 2575, 2577, 2579, 2581, 2583, 2585, 2587, 2589, 2591, 2593, 2595, 2597, 2599, 2601, 2603, 2605, 2607, 2609, 2611, 2613, 2615, 2617, 2619, 2621, 2623, 2625, 2627, 2629, 2631, 2633, 2635, 2637, 2639, 2641, 2643, 2645, 2647, 2649, 2651, 2653, 2655, 2657, 2659, 2661, 2663, 2665, 2667, 2669, 2671, 2673, 2675, 2677, 2679, 2681, 2683, 2685, 2687, 2689, 2691, 2693, 2695, 2697, 2699, 2701, 2703, 2705, 2707, 2709, 2711, 2713, 2715, 2717, 2719, 2721, 2723, 2725, 2727, 2729, 2731, 2733, 2735, 2737, 2739, 2741, 2743, 2745, 2747, 2749, 2751, 2753, 2755, 2757, 2759, 2761, 2763, 2765, 2767, 2769, 2771, 2773, 2775, 2777, 2779, 2781, 2783, 2785, 2787, 2789, 2791, 2793, 2795, 2797, 2799, 2801, 2803, 2805, 2807, 2809, 2811, 2813, 2815, 2817, 2819, 2821, 2823, 2825, 2827, 2829, 2831, 2833, 2835, 2837, 2839, 2841, 2843, 2845, 2847, 2849, 2851, 2853, 2855, 2857, 2859, 2861, 2863, 2865, 2867, 2869, 2871, 2873, 2875, 2877, 2879, 2881, 2883, 2885, 2887, 2889, 2891, 2893, 2895, 2897, 2899, 2901, 2903, 2905, 2907, 2909, 2911, 2913, 2915, 2917, 2919, 2921, 2923, 2925, 2927, 2929, 2931, 2933, 2935, 2937, 2939, 2941, 2943, 2945, 2947, 2949, 2951, 2953, 2955, 2957, 2959, 2961, 2963, 2965, 2967, 2969, 2971, 2973, 2975, 2977, 2979, 2981, 2983, 2985, 2987, 2989, 2991, 2993, 2995, 2997, 2999, 3001, 3003, 3005, 3007, 3009, 3011, 3013, 3015, 3017, 3019, 3021, 3023, 3025, 3027, 3029, 3031, 3033, 3035, 3037, 3039, 3041, 3043, 3045, 3047, 3049, 3051, 3053, 3055, 3057, 3059, 3061, 3063, 3065, 3067, 3069, 3071, 3073, 3075, 3077, 3079, 3081, 3083, 3085, 3087, 3089, 3091, 3093, 3095, 3097, 3099, 3101, 3103, 3105, 3107, 3109, 3111, 3113, 3115, 3117, 3119, 3121, 3123, 3125, 3127, 3129, 3131, 3133, 3135, 3137, 3139, 3141, 3143, 3145, 3147, 3149, 3151, 3153, 3155, 3157, 3159, 3161, 3163, 3165, 3167, 3169, 3171, 3173, 3175, 3177, 3179, 3181, 3183, 3185, 3187, 3189, 3191, 3193, 3195, 3197, 3199, 3201, 3203, 3205, 3207, 3209, 3211, 3213, 3215, 3217, 3219, 3221, 3223, 3225, 3227, 3229, 3231, 3233, 3235, 3237, 3239, 3241, 3243, 3245, 3247, 3249, 3251, 3253, 3255, 3257, 3259, 3261, 3263, 3265, 3267, 3269, 3271, 3273, 3275, 3277, 3279, 3281, 3283, 3285, 3287, 3289, 3291, 3293, 3295, 3297, 3299, 3301, 3303, 3305, 3307, 3309, 3311, 3313, 3315, 3317, 3319, 3321, 3323, 3325, 3327, 3329, 3331, 3333, 3335, 3337, 3339, 3341, 3343, 3345, 3347, 3349, 3351, 3353, 3355, 3357, 3359, 3361, 3363, 3365, 3367, 3369, 3371, 3373, 3375, 3377, 3379, 3381, 3383, 3385, 3387, 3389, 3391, 3393, 3395, 3397, 3399, 3401, 3403, 3405, 3407, 3409, 3411, 3413, 3415, 3417, 3419, 3421, 3423, 3425, 3427, 3429, 3431, 3433, 3435, 3437, 3439, 3441, 3443, 3445, 3447, 3449, 3451, 3453, 3455, 3457, 3459, 3461, 3463, 3465, 3467, 3469, 3471, 3473, 3475, 3477, 3479, 3481, 3483, 3485, 3487, 3489, 3491, 3493, 3495, 3497, 3499, 3501, 3503, 3505, 3507, 3509, 3511, 3513, 3515, 3517, 3519, 3521, 3523, 3525, 3527, 3529, 3531, 3533, 3535, 3537, 3539, 3541, 3543, 3545, 3547, 3549, 3551, 3553, 3555, 3557, 3559, 3561, 3563, 3565, 3567, 3569, 3571, 3573, 3575, 3577, 3579, 3581, 3583, 3585, 3587, 3589, 3591, 3593, 3595, 3597, 3599, 3601, 3603, 3605, 3607, 3609, 3611, 3613, 3615, 3617, 3619, 3621, 3623, 3625, 3627, 3629, 3631, 3633, 3635, 3637, 3639, 3641, 3643, 3645, 3647, 3649, 3651, 3653, 3655, 3657, 3659, 3661, 3663, 3665, 3667, 3669, 3671, 3673, 3675, 3677, 3679, 3681, 3683, 3685, 3687, 3689, 3691, 3693, 3695, 3697, 3699, 3701, 3703, 3705, 3707, 3709, 3711, 3713, 3715, 3717, 3719, 3721, 3723, 3725, 3727, 3729, 3731, 3733, 3735, 3737, 3739, 3741, 3743, 3745, 3747, 3749, 3751, 3753, 3755, 3757, 3759, 3761, 3763, 3765, 3767, 3769, 3771, 3773, 3775, 3777, 3779, 3781, 3783, 3785, 3787, 3789, 3791, 3793, 3795, 3797, 3799, 3801, 3803, 3805, 3807, 3809, 3811, 3813, 3815, 3817, 3819, 3821, 3823, 3825, 3827, 3829, 3831, 3833, 3835, 3837, 3839, 3841, 3843, 3845, 3847, 3849, 3851, 3853, 3855, 3857, 3859, 3861, 3863, 3865, 3867, 3869, 3871, 3873, 3875, 3877, 3879, 3881, 3883, 3885, 3887, 3889, 3891, 3893, 3895, 3897, 3899, 3901, 3903, 3905, 3907, 3909, 3911, 3913, 3915, 3917, 3919, 3921, 3923, 3925, 3927, 3929, 3931, 3933, 3935, 3937, 3939, 3941, 3943, 3945, 3947, 3949, 3951, 3953, 3955, 3957, 3959, 3961, 3963, 3965, 3967, 3969, 3971, 3973, 3975, 3977, 3979, 3981, 3983, 3985, 3987, 3989, 3991, 3993, 3995, 3997, 3999, 4001, 4003, 4005, 4007, 4009, 4011, 4013, 4015, 4017, 4019, 4021, 4023, 4025, 4027, 4029, 4031, 4033, 4035, 4037, 4039, 4041, 4043, 4045, 4047, 4049, 4051, 4053, 4055, 4057, 4059, 4061, 4063, 4065, 4067, 4069, 4071, 4073, 4075, 4077, 4079, 4081, 4083, 4085, 4087, 4089, 4091, 4093, 4095, 4097, 4099, 4101, 4103, 4105, 4107, 4109, 4111, 4113, 4115, 4117, 4119, 4121, 4123, 4125, 4127, 4129, 4131, 4133, 4135, 4137, 4139, 4141, 4143, 4145, 4147, 4149, 4151, 4153, 4155, 4157, 4159, 4161, 4163, 4165, 4167, 4169, 4171, 4173, 4175, 4177, 4179, 4181, 4183, 4185, 4187, 4189, 4191, 4193, 4195, 4197, 4199, 4201, 4203, 4205, 4207, 4209, 4211, 4213, 4215, 4217, 4219, 4221, 4223, 4225, 4227, 4229, 4231, 4233, 4235, 4237, 4239, 4241, 4243, 4245, 4247, 4249, 4251, 4253, 4255, 4257, 4259, 4261, 4263, 4265, 4267, 4269, 4271, 4273, 4275, 4277, 4279, 4281, 4283, 4285, 4287, 4289, 4291, 4293, 4295, 4297, 4299, 4301, 4303, 4305, 4307, 4309, 4311, 4313, 4315, 4317, 4319, 4321, 4323, 4325, 4327, 4329, 4331, 4333, 4335, 4337, 4339, 4341, 4343, 4345, 4347, 4349, 4351, 4353, 4355, 4357, 4359, 4361, 4363, 4365, 4367, 4369, 4371, 4373, 4375, 4377, 4379, 4381, 43

UNITED STATES PATENT OFFICE.

JOSEPH S. WILLIAMS, OF RIVERTON, NEW JERSEY.

TRANSPORTATION SYSTEM.

1,050,320.

Specification of Letters Patent. Patented Jan. 14, 1913.

Application filed December 8, 1906. Serial No. 346,891.

To all whom it may concern:

Be it known that I, JOSEPH S. WILLIAMS, a citizen of the United States, residing at Riverton, in the county of Burlington, State 5 of New Jersey, have invented a new and useful Transportation System, of which the following is a specification.

My present invention consists of a novel construction of a transportation system 10 comprising subway and subaqueous lines which are connected in a water proof union with each other, and are provided with definite and reliable standards of reinforced construction having reliable standards of 15 bridging capacity and resistance to leakage and pressure, whereby passengers and freight may be conveyed with absolute safety to subway line parts of the system into traffic connection with railways, trolley lines and road ways on opposite sides of 20 the water way.

It further consists in a novel transportation system wherein the foundation bed is reinforced throughout its length to definite 25 standards, such bed being further reinforced on bridging unit section lines, thereby adapting the same to receive a tunnel construction having bridging capacity in each unit length thereof sufficient to 30 support the maximum traffic.

It further consists of a novel transportation system wherein a continuity of water proofing, bridging and reinforcing elements is obtained from one end of the system to 35 the other.

It further consists in a novel transportation system wherein a working chart is established above the traffic line which defines the excavating, bridging, grading and balancing 40 of the tunnel line channel in the water bed and the reinforcements of such bed, whereby transportable tunnel structures may be established on the completed foundation bed in accurate alinement.

It further consists of other novel features of construction, all as will be hereinafter 45 fully set forth.

For the purpose of illustrating my invention I have shown in the accompanying 50 drawings one embodiment thereof since the same will give satisfactory and reliable results in practice although it is to be understood that the various instrumentalities of which my invention consists can be vari-

ously arranged and organized and that my 55 invention is not limited to the exact arrangement and organization of these instrumentalities as herein set forth.

Figure 1 represents a plan view of a multiple line transportation system embodying 60 my invention. Fig. 2 represents a sectional elevation of the system shown in Fig. 1. Fig. 3 represents a side elevation partly in section, of a portion of the system under construction. Fig. 4 represents an end elevation of Fig. 1. Fig. 5 represents a perspective view showing, in section, one of the lap joint unions. Fig. 6 represents a perspective view of one of the alined piers 65 and certain of its adjuncts. Fig. 7 represents a perspective view of one tunnel section as placed and another as being lowered to placement, with certain of their adjuncts. Fig. 8 represents a perspective view of multiple tunnel structures, certain of the parts 70 being shown in section. Fig. 9 represents a perspective view of a portion of a multiple tunnel structure, partly broken away in order to more clearly show the construction 75 thereof.

Similar numerals of reference indicate 80 corresponding parts in the figures.

Referring to the drawings:—in order to more clearly set forth the construction of my novel transportation system I will, in 85 the detail description thereof, in so far as is practical, follow out the different steps of construction in the logical sequence in which they take place.

The working chart.—One of the novel 90 features of my construction is the establishment of a visible working chart above the water line, in the present instance such chart being shown as located on platforms 7 carried by the side pilings 5. The exact center 95 line of the system is designated by 1, and 3—3 designate the width of the tunnel construction and otherwise the lines for defining and establishing a minimum width of the line of the tunnel grade. 4—4 designate 100 approximate alining lines equidistant from the longitudinal center line 1 and upon which side pilings 5—5 are established to operate as approximate alining members for the transportable tunnel sections, as such are 105 being located for placement over the graded and equipped foundation bed. 6 designates section lines which define the length of a

section of a bridging unit of tunnel construction and the section lines 19 define the length of a bridging unit in a tunnel section or the ends of a tunnel section. 9 and 10 5 designate section lines for the accurate placing of the tunnel sections. All of these section lines and the other necessary lines to indicate the work to be performed are indicated on the platforms 7 or other suitable means above the water level.

10 *Construction of the foundation bed.*—In the building of my novel system, the foundation bed may be constructed in its entirety from one end to the other or certain 15 parts thereof may be built up as the work progresses and the tunnel sections established on such foundation bed. The channel is first dredged to the sub grade line 16 either before or after the side pilings 5—5 20 have been established and these pilings, if desired, may be driven throughout the entire length of the tunnel line. The dredged and excavated channel 16 may now be reinforced with pilings 90 which are afterward capped 25 with ballast of any desired material 91 to or in proximity to the tunnel grade line 15. At bridging unit distances apart the foundation bed is reinforced by piling the same and reinforcing the piling with ballast with 30 or without metal reinforcements therein, thereby forming grade line supports 2, which are seen most clearly in Figs. 3, 5 and 7 and the purpose of which will hereinafter appear. The entire distance between the grade 35 line piers 2 may, if desired, be equipped with pilings 90 capped with ballast, such as concrete or cement 91 to the grade line 15 or in proximity thereto, as will be understood by reference to Fig. 3. The length of 40 a tunnel section will depend upon the number of bridging unit lengths in such section, and on certain of the grade line supports 2, especially those at the ends of meeting tunnel sections when placed, I establish a novel 45 construction of piers 85 which will now be described.

50 *The piers 85.*—In order that the tunnel sections may be automatically aligned when lowered to placement on the foundation bed and its reinforcements, I establish at the 55 ends of meeting tunnel sections and otherwise throughout the tunnel line, if desired, aligning piers 85 which are composed of the side walls 5—5, on which the platforms 7 are established. The side walls 5—5 are 60 reinforced by guiding standards 18, the inner faces of which are inclined, as will be understood from Figs. 4, 6 and 7. These approximate aligning standards 18 register 65 with the exact aligning standards 17, the construction being such that chambers 54 are formed on each side of the pier 85 which communicate with the channel 207 in the bottom of said piers. The chambers 54 are 70 preferably provided with metal elements 209

therein. The space beneath the piers 85 is piled and then ballasted with concrete or cement to the tunnel grade line 15, such ballasting material having embedded therein the metal elements 209 in order to reinforce 75 the foundation portion to any desired extent, it being understood that each pier 85 is provided with a channel 207 communicating with the chambers 54.

75 11—11 designate guide standards on the inner face of the piers. The channels 207 and chambers 54 are filled with ballast after the tunnel sections have been laid, in order to encompass the meeting ends of tunnel sections with a sealing material, as will be 80 clearly described in connection with the manner of sealing the meeting ends of tunnel sections.

85 *The tunnel sections.*—13 and 14 designate the tunnel sections as seen in Figs. 3 and 7. One novel feature in the construction of the tunnel section is the building up of a bridging construction or framework 210, the same consisting of the vertical beams 24 united to the roof beams 27 and the foundation beams 28, it being most clearly seen in Figs. 5 and 9 that knee braces 31 are employed in order to more clearly connect the parts.

90 25 designates a lattice work reinforcement of metal which is connected with the plates 95 26 which are secured to the vertical beams 24.

95 22, 23, 83 and 84 designate cords secured to the framework 210 in any suitable manner and which extend in continuity throughout the tunnel construction after the sections have been lowered in position and joined together. The bridging framework 210 is embedded in reinforcing material 56, such as concrete or cement and enveloped by water 100 proofing 57, as well as an inner lining member 49, which, if desired, extends throughout the entire tunnel line and is employed at the ends of each tunnel section. This lining member 49 consists of a metal lining built 105 up on the face of the knee braces 31, on the vertical beams 24, and the top and floor beams 27 and 28 respectively. Transversely disposed plates or beams 216 are shown at the upper and lower portions on the inner 110 sides of the framing 210, as best seen in Fig. 8 in order to reinforce the same against transverse strains and these plates may form a continuation of the inner lining member 115 49 and be extended along the roof and floor parts and along the face or faces of the vertically disposed elements of the framing 210, all of which are preferably water proofed with a suitable unoxidizable material, such as pitch and asphaltum and embedded in pitch or asphaltum, or a filling 120 of concrete or cement 56 may be employed which will completely embed the metal elements.

125 The water proofing 57 is in union with the 130

metal 58 within which the elements of the framing 210 are embedded to and flush with the inner surface of such framing elements, along which another line of water proofing 64 may be established, if desired, to encompass the tunnel way and be united with the water proofing at the ends of tunnel sections as seen mostly clearly in Fig. 3 as will be more fully described. Such water proofing 64 may be reinforced by metallic elements 74 embedded therein with the meeting ends in contact or lapping each other to any desired extent and arranged longitudinally, transversely or in any other desired direction. The tunnel way is built up with a filling and reinforcing ballast of masonry of heat resisting material 73 in intimate contact therewith and extending thereover to the inner face 70 of the tunnel way, as will be best understood from Figs. 8 and 9. The inner layer of water proofing 64 may be carried over the inner face of the framing 210 back of the knee braces 31 or over the inner face of the framing 210 and the inner faces of the I-beams into union with longitudinal and transverse layers of suitable material 200 acting as a water proofing and reinforcement material of the framing 210, as shown at the upper and lower corners, see Figs. 8 and 9, extending over and under the vertical outside framing and over and under the intermediate longitudinal framing between the multiple tunnel ways 96 so that the structural elements and reinforcements encompassing the tunnel ways will be sectionalized to prevent any leakage spreading and thus localize the same to one section. Water proofing 63 and 57 by which the tunnel way is encompassed and by which the bridging framing 210 is protected and reinforced is shown as being reinforced by an apertured metal member 217, best seen in Fig. 8, so that the outer body of water proofing 63 forms a unit with the inner water proofing 57 and otherwise a unit of reinforced water proofing and reinforcing sheathing in intimate contact and union with the material 56 and 65 in which the metal framing 210 is embedded. The water proofing 57 is in intimate contact and union with the reinforcing material in which the metal framing 210 is embedded and this is reinforced by metal sheathing as designated by 218, and a wooden sheathing as designated by 219, which is covered by an outer layer of water proofing 63 of asphaltum, pitch or other suitable material, which is maintained in intimate contact and union with the outer surface with or without bridging or lathing work to provide for such results. The water proofing on the inner and outer parts in such cases is carried into union with the water proofing at the ends of the structures through the medium of the water proofing and reinforcing

unit 65, as will be best understood by reference to Fig. 9. In case of the water proofing being reinforced with multiple layers of wooden planks or equivalent material 61, the water proofing may be further reinforced by layers of water proofing 62 between the respective layers of wood, see the right hand portion of Fig. 8. The foundation portion of the transportable tunnel sections is provided with the foundation strips 36 which serve to confine the ballast beneath the sections when placed, it being noted that the foundation part is provided with ballasting ports 46 having water proof seals 48 adapted to be driven out and also with water tight capped members 47, whereby they may be capped subsequently to have the tunnel sections ballasted into union with the foundation bed and its reinforcements. It will be noticed that the water proofing of the tunnel structure entirely surrounds the ballasting ports 46 so that there is no liability of leakage at such points.

Under one method of construction I build the sections 13 and 14 to an inner encompassing line, such as 64, and subsequently to the tunnel alignment, build up the same to the line 70 with or without employing metal reinforcements 74 or other reinforcing or lining metal elements embedded in the filling material between the defining lines of 64 and 70.

Between the defining lines 76 and 77 I have shown such space as provided with a backing or filling of cement or concrete with reinforcing metal 78 embedded therein between the lines of water proofing 64 and the line 70. The construction between the lines 77 and 79 is shown reinforced by metal which is embedded in waterproofing and concrete. Between the lines 79 and 80 the construction is shown reinforced by material, either embedded therein or on the inner face thereof and with a further supporting and reinforcing part consisting of cement, vitrified brick, or equivalent material laid in cement or other desired material to the inner facing line 70. Between the lines 80 and 76 the construction is shown as provided with reinforcing material consisting of expanded, woven or perforated metal or its equivalent 81, with such reinforced section further supported and reinforced by concrete, cement or other suitable material or masonry built up to the inner line 70.

At 82 Fig. 8 I have shown suitable arched or bended bars which may be employed in said part with or without longitudinal elements of like material therewith and be embedded with a heat resisting material employed for filling to the inner line 70 around the tunnel passageway 96 throughout the length of the unit or the section. Such transverse reinforcing bars 82 may be embedded to encompass the passageway and

if desired in conjunction with longitudinal bars of apertured plate, sheet metal fabric or reinforcing elements may be embedded to the inner line of the tunnel way encompassing construction between the inner face of the framing 210 or the line of water proofing 64 to the inner line 70 thereof. The layers 201 and 202 of water proofing will thus localize any leakage to the area 10 of the section encompassed thereby. The longitudinal layers 200 extend from the construction into union with the encompassing water proofing filling and reinforcing unit 65 at the end of the sections.

15 Metal reinforcing bars 203 extend longitudinally through the construction and are located in the concrete or other reinforcing material between the knee braces 31 and the inner metal lining member 49. Similar bars 204 are employed at the upper end 20 of the structure, such bars being embedded in the concrete between the knee braces 31 at the upper end of the structure and the metal line or frame. These metal cord 25 members 204 serve to overcome the lateral strain to which the tunnel structure is subjected when placed in position on the pier grade line supports 2. The cords 203 and 204 of adjoining sections may be connected 30 or joined together by lapping elements in any suitable manner and be embedded in reinforcing material so as to form continuous reinforcing elements embedded in concrete through a series of unit lengths and 35 through the union of meeting ends of tunnel sections so as to provide a continuous reinforcement throughout a definite section or throughout the entire length of the tunnel line.

40 205 designates metallic bars extending longitudinally along the flooring of the upper portion of the foundation or bed in the outer portion of the water proofing zone between the ballasting ports 46 and under 45 the longitudinal girders or cords with such bars embedded in water proofing in order to operate as an outer reinforced water proof element in the floor portion and to increase the bridging capacity and reinforcement of the foundation and bed.

50 It will now be apparent that the foundation parts of the water proof construction are provided with water proofing carried by the sides of the ballasting ports 46 to 55 a water tight capping member 47 and that the channel ways of the ports are closed by water proof cement seals 48, which prevent passage of water through the tunnel way, and that such can be driven out on the bed 60 in order to ballast the same through the ports, and subsequently to the ballasting of the foundation through the ports, the cap 47 can be reinforced and water proofed and embedded in cement or asphaltum to the 65 inner line 70. The water proofing 64 may

be established on the flooring and preferably so as to envelop and cap the capping members 47 of the ballasting ports 46 and such water proofing is reinforced with an inner lining element of cement, concrete or cement masonry with or without metal reinforcements but I preferably embed therein such reinforcements. be established on the flooring and preferably so as to envelop and cap the capping members 47 of the ballasting ports 46 and such water proofing is reinforced with an inner lining element of cement, concrete or cement masonry with or without metal reinforcements but I preferably embed therein such reinforcements. The foundation parts 36 not only serve to form ballasting compartments but also tensile reinforcing elements encompassing the area of the bed of construction. It is practicable to employ any desired depth of construction in the parts 36 to secure greater reinforcement on longitudinal and transverse lines in the foundation bed and otherwise to provide any desired depth in the compartments below the tunnel way construction. The sections are preferably provided with plate forms 206 extending throughout the tunnel line on opposite sides of the tracks 55. The foundation portion of the tunnel section is provided with the drainage conduits 215 which extend from one end of the tunnel end to the other and communicate with the drainage wells 21, the latter being seen in Fig. 2, said wells forming a water proof chamber in the foundation bed or within one of the piers 85 and being joined in water proof union with the conduits 215. The ends of each section are provided with bulk heads 40 having 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735

tinuity throughout the system, but such method is not as rapid, economical or favorable as the system in which transportable tunnel sections are established in proper alignment along the graded and alined bed and in continuous ballasted union therewith.

The tunnel section is provided with the bulk heads 40 and transported by suitable means to proper alinement above the foundation bed between the side walls or pilings 5-5 and beneath the platforms 7 so that when lowered to placement on the foundation bed, the ends of the sections will rest on alining piers 85, the guide bars 12 carried by a tunnel section co-acting with the guides 11-11 and the co-acting elements 41 and 42 of the joining structures interlocking with each other and the jaws 35 also serve to accurately bring the two tunnel sections into proper alinement, so that the foundation part rests on the grade line supports 2. As the tunnel section is lowered to place it will be seated upon the foundation bed in accurate alinement, owing to the employment of the approximate guides 18 and the exact guides 17. The chambers 54 and the channel 207 are now filled with concrete or cement and a box or cradle 68 is placed above the meeting ends of the tunnel section and filled with concrete or cement with or without metallic elements 209 embedded therein so that the meeting ends of adjoining sections are encompassed by a water proof seal of concrete or cement reinforced to any desired standard by metal elements embedded therein such as the bars 209. The bulk heads 40 may now be broken down, if desired, and the tunnel sections placed under air pressure and the lap joint union 49 of the meeting structures is formed, the cords 22, 23, 83 and 84 being joined together by lapping cords 97 and 98 and a union is made of the cord elements 203 and 204 and the other cord elements and the end plates 39 are united together. If desired the lap joint may be first made in the air lock chamber 66 between the bulk heads 40, as will be understood by reference to Fig. 5. A union is made of the cords 97 and 98 at the back of the lining member 49 and the lap joint is built up in the manner before described with reference to the tunnel construction, it being understood that a unit of water proofing 65 is formed at the meeting ends which unites with the separate layers of water proofing in the tunnel section.

In case the continuous metal sheathing on the outside of the lining member 49 is employed combined with the cords 22, 23, 84, 97 and 98 and the tunnel way encompassing bridging framing 210, a bridging construction will be provided in the sides of the structure and between the multiple tunnel way structures, including trussed plate gird-

ers having upper and lower cords 22, 23, 83 65 and 84 with the flooring and roofing elements combined therewith, reinforced by knee brackets 31 and embedded in reinforcing material 56 and 57 in which additional reinforcing elements may be embedded in 70 the upper and lower parts of the structure in the space confined by the knee brackets 31 and otherwise on the inner face of the framing 210, whereby any desired standards of reinforcement against lateral as well as vertical strain may be obtained. The unit of water proofing 65 at the ends of the meeting sections is connected from the top of the flooring parts of the construction through or along the sides of the intermediate girder 80 of the multiple tunnel way by embedding the metal in water proofing or otherwise by extending a layer of water proofing 64 on one or both sides of such intermediate girder from the water proofing in the roof to the 85 water proofing in the foundation part. The inner lining 49 is backed by the water proofing 65 which is in intimate and water tight union therewith. The water proofing 65 is also shown in water proof union with the water proofing 67 shown as extending over the inner surface of and embedding the inner lining member 49 from one section to the other. The water proofing 67 is embedded in reinforcing material or reinforced by heat resisting material to the line 70, whereby continuity of water proofing and reinforcements and of the bridging elements 210 is established for any given length of tunnel way and if desired throughout the 100 length of the subaqueous tunnel construction from one shore to the other. To effectually and similarly water proof the union I fill the space between the lines 57 and 64 or the space between the outer bounding element 105 of such part and the back of the lining and lapping member 49 with suitable water proof material or materials to form a unit water proofing 65 at the ends of both of the sections which are united. The union of two tunnel sections having been made, the other sections are lapped and united in a similar manner and the next operation is the ballasting of the tunnel line into union with the foundation bed and its reinforcements. This ballasting may be carried out wholly or partially through the ballasting ports 46, it being apparent that when the seals 48 have been removed, the material such as grouting, cement or concrete may 110 be passed through such ports so as to completely fill the compartments formed by the foundation members 36 on the foundation bed so that the foundation part of the tunnel will be united with the foundation bed. 115 The ballasting ports are filled with sealing material and then covered by the caps 47, after which the latter are covered with con-

crete reinforced with metallic elements to the inner line of the tunnel way, as hereinbefore explained.

If desired, pilings 90 may be driven 5 through the ballasting ports in order to reinforce the foundation bed to any desired standard of resistance. The side pilings 5-5 are now cut off at a desired height above the tunnel. The space between the 10 side pilings and the tunnel sections is now filled with ballast from the vessels 93, which latter are also preferably provided with the cables 92 which support the tunnel sections when being lowered to placement. The ballast 15 may be tamped by any desired means and the tunnel sections completely embedded and ballasted to any desired depth.

Shore connections and union of the traffic lines therewith.—At the shore ends of the 20 tunnel line I preferably establish a novel construction of viers or docks 20 or otherwise at desired points throughout the tunnel line, such docks or piers having water proof reinforced encompassing 25 walk 101 extending from the water proof reinforced flooring 105 to a safe distance above the water line so that the water proof chambers of such structures may first serve for the laying and constructing of the trans- 30 portable tunnel section and afterward as subwater line passageways in order to provide other lines of passage through the subway and subaqueous traffic lines of the system. The dock structure 20 is provided 35 with a water proofing 119 which extends entirely around the structure and into union with the intermediate flooring 128, the wharf flooring 106 and the metal framing 125, which latter is embedded in concrete or 40 some suitable water proofing. The foundation of the dock structure 20 is reinforced by piling capped with concrete or other ballast so that such flooring will have the same supporting capacity as the foundation bed of 45 the tunnel line. The subwater line chamber of the dock 20 is provided with a system of side tracks 214 and cross over roads 213 in connection with the other lines of tracks 87, which are shown extending through the 50 connection to opposite shores and into subwater line subway 143 to connect with the shore transportation systems. The subwater line 143 is provided with water proofing in reinforced construction and united to the 55 water proofing 119 of the dock 20, it being seen in Fig. 1 that a line of water proofing 137 encompasses the subway construction and occupies all the space between such construction and the vertical reinforced walls 60 of the dock structure 20.

The subway 143 consists of a water proof reinforced construction with its water proofing elements 144 extending in continuity and encompassing the passageway and reinforced by an intermediate inner element

of construction which is established in reinforced union with the outer element and such construction is united in water proof union with the dock structure 20. The subway 143 extends on the shore to such distance above the water level as to prevent any leakage into the passageway of the subway.

The dock 20 consisting of the outer encompassing wall 107 of the water proofing 119 and the inner construction 125, together with the foundation which extends to a desired depth, insure the stability of the tunnel structure. The area of construction encompassed by the wall 107 is excavated to a line below the tunnel and subway grade 70 ballast or ballast masonry 117, which extends over the entire floor area and joins with the water proofing 119, which covers the entire inner face of the wall 107 and 75 extends into union with the water proofing 119 of the wharf floor 106. The tunnel grade floor 105 is reinforced by a ballasted covering suitably water proofed and preferably provided with girders or reinforced 80 metal or framing embedded in asphaltum or water proof material, which is united with the water proofing on the inner face of the walls 107. The inner framing 125 is embedded in water proofed ballast or concrete ballast or cement masonry after first 85 being preferably coated with a water proofing material which will preserve the metal against any possibility of oxidization. The subway lines 143 may be built by driving 90 side pilings and an opening cut or by driving a shield from the chamber of the wharf structure 20, but whatever method shall be employed it is necessary to provide reliable 95 standards of resistance against leakage, breakage and uncertainty in the construction.

The dock structures may be provided with drainage wells 21 constructed in a similar manner to the drainage wells in the foundation bed of the tunnel line, it being understood that these wells communicate with the conduits 215, seen in Fig. 8. The trans- 100 portable sections of the tunnel may be built up in the subwater line chambers of 105 the dock 20, in coffer-dam, or in any other suitable places, and may be provided with the requisite standards of floatability either in the structures themselves or by equipping the same with buoyant vessels which are 110 equipped with any suitable means to vary their buoyancy, whereby the structures may be located in perfect control into alignment on the foundation bed. By constructing 115 tunnel sections independently of the tunnel system it is practicable to have such sections ready for the completion of the entire line by the time the water bed shall be dredged, graded and equipped with its reinforce- 120 ments. By such methods any part or all 125 130

parts of the system may be in the course of construction at the same time and when the transportable sections are completed they can be very rapidly placed in accurate alignment and water tight union on the foundation bed.

The longitudinal bridging elements of construction may have a bridging unit volume of ten feet, more or less, for a maximum load, but I prefer to reinforce the construction with longitudinal bridging unit elements having a bridging unit volume equal to or exceeding the length of the wheel base of at least one and preferably two in series of the heaviest loaded engines or vehicles and the load carried thereby. With a bridging unit of one hundred feet in length and twenty two feet in height with a capacity of three tons per lineal foot, suitably supported at the ends, such unit would operate as a bridging unit of construction with a traffic load bridging volume of three hundred tons while such unit of construction in its reinforced union with the foundation bed 25 22 feet by one hundred feet, will have a bridging load supporting capacity of twenty two hundred square feet with a load supporting volume of at least twenty two hundred tons per unit of construction. In a continuous bridging and reinforcing foundation bed with such a standard unit of construction the unit under operative traffic conditions will always have a coöperative unit of like capacity as an addition thereto from in advance and back of the load, not only throughout an extended area of resistance bed but of the bed in advance and back of the load and in continuity throughout the tunnel construction.

8 I have shown and described the structures and means by which subaqueous tunnels can be established with reliable standards of capacity and construction and by which an absolute continuity of the bridging construction and reinforcements may be established from shore to shore or to my novel wharf structures but the exact construction or plans of procedure may vary greatly in actual practice.

10 It will now be apparent that I have devised a novel and useful transportation system which embodies the features of advantage enumerated as desirable in the foregoing and while I have in the present instance shown and described one embodiment thereof which will give satisfactory and reliable results it is to be understood that the same is susceptible of modification in various particulars without departing from the spirit and scope of the invention or sacrificing any of its advantages.

Having thus described my invention, what I claim as new and desire to secure by Letters Patent, is:—

65 1. A transportation system consisting of

shore terminals in water tight union with a bridging tunnel construction having bridging capacity in each unit length thereof, reinforced in its inner face by a series of cords embedded in water proofing and concrete and united with the shore terminals, the tunnel structures being ballasted into union with the foundation bed thereunder. 70

2. A transportation system, consisting of shore terminals in water tight union with a subwater line tunnel having a bridging construction in each unit length thereof embedded in concrete and water proofing material and having its inner face built up with metal joined in continuity and embedded in concrete and water proofing material to the inner tunnel line and having its outer face embedded in ballast, and the bottom of the tunnel construction ballasted into union with the foundation bed thereunder. 80

3. A transportation system consisting of an excavated, graded and ballasted foundation bed equipped with side pilings or walls a tunnel having bridging construction in each unit length thereof embedded in concrete and water proofing material, such tunnel construction being ballasted into union with the ballasted bed and the side walls and embedded to cover, and shore terminals in water tight union with said tunnel. 90

4. A transportation system consisting of a wharf structure having a wharf floor connected with a surface roadway system and having a subwater line chamber, a subway line in water proof union with such chamber, and a subaqueous tunnel in water proof union with said chamber. 100

5. A transportation system consisting of a wharf structure having a water proof chamber extending below the water line, and a subway in water proof connection with such chamber. 105

6. A transportation system consisting of wharf structures on opposite shores of a water way having water proof chambers extending below the water line, a subaqueous tunnel construction having water proof connection with such chambers, and conduits for draining and removing liquids from the subwater line system. 110

7. A transportation system including wharf structures having water proof chambers extending below the water line, a subaqueous tunnel in water proof connection with such chambers and extending therethrough, drainage channels in the tunnels, drainage wells in the foundation bed communicating with such channels, and conduits for withdrawing water from such channels. 120

8. A transportation system consisting of shore connections having subwater line water proof chambers, a subaqueous tunnel in water proof connection with such chamber. 125

- bers, said tunnel consisting of a bridging construction in each unit length thereof, ballasted into union with a foundation bed, and reinforced by pilings and ballast to bridging capacity in each unit length thereof.
9. A transportation system, including a wharf structure having a water proof chamber extending below the water line, and a subaqueous tunnel joined in water proof union therewith, said tunnel being provided with a continuity of cords throughout its length embedded in concrete and reinforcing material and having a bridging construction in each unit length thereof, and the tunnel being ballasted into union with a graded and resistance alining foundation bed thereunder.
10. A transportation system, consisting of shore connections and a subaqueous tunnel in water proof union therewith, the tunnel consisting of a bridging construction having upper and lower cord members extending in continuity throughout the construction, and the tunnel being united in reinforced union with its foundation bed.
11. A transportation system, consisting of shore connections in water proof union with a subaqueous tunnel, said tunnel having a bridging framing provided with upper and lower cord members, reinforced with corner knee brackets on the sides of the tunnel way to the roof and floor, the cord members and the brackets being embedded in concrete and water proofing material.
12. A transportation system, consisting of shore terminals in water proof union with a tunnel, having a bridging framing with the roofing and flooring parts of such framing, reinforced between the passageways by longitudinal bridging girders and braces from the roof and floor to both sides thereof, such framing girders and braces being embedded in concrete and water proofing material and the tunnel being ballasted into union with its bed.
13. A transportation system, consisting of shore connections in water tight union with a tunnel, said tunnel consisting of a bridging framing reinforced by girders extending in continuity throughout the tunnel line, the framing and girders being embedded in concrete and reinforcing material and enveloped by an outer casing member which is in reinforced union with the foundation bed.
14. A transportation system, consisting of shore connections in water proof union with a tunnel, the tunnel having a continuous sheathing surrounding a bridging framing, embedded in concrete and water proofing material, the sheathing being embedded in water proofing material, and the tunnel being ballasted into union with its foundation bed.
15. A transportation system, consisting of shore connections in water proof union with a tunnel, the tunnel having trussed plate girders extending from the floor to the roof of the structure and joined with the transverse roof and flooring members reinforced by braces and embedded in concrete and reinforcing material, the girders being encompassed by a sheathing element embedded in water proofing and ballasted into union with the foundation bed.
16. A transportation system, consisting of shore connections in water proof union with a subaqueous tunnel, consisting of a bridging framing embedded in concrete and water proofing material and having a girder element intermediate the sides thereof and united with the roofing and flooring framing to form a plurality of passageways, the tunnel being ballasted into union with its foundation bed.
17. A transportation system, consisting of shore connections in water proof union with a subaqueous tunnel, said tunnel way having a central girder member in water proof union with the roofing and flooring of the tunnel and forming multiple tunnel ways provided with side walks, and the tunnel being ballasted into reinforced union with its bed.
18. A transportation system, consisting of shore connections in water proof union with a subaqueous tunnel having multiple tunnel ways encompassed by a bridging framing having upper and lower cords embedded in concrete and water proofing material and extending in continuity throughout the tunnel line, the tunnel being ballasted throughout its entire length into union with its foundation bed.
19. A transportation system including shore connections having a sub water line water proof chamber provided with a foundation reinforced to bridging capacity, and a subaqueous tunnel united in water proof union with such chamber.
20. A transportation system including wharf structures each having a water proof chamber extending below the water line provided with intercommunicating tracks, a subway line in water proof union with said chamber, and a tunnel in water proof union with said chamber.
21. A transportation system consisting of shore connections having a floor above the water line connected with a surface roadway system, and having a sub water line chamber, a subway line in water proof union with such chamber, and a tunnel having a bridging construction united with said chamber and supported on piers at predetermined distances apart and ballasted into union with the bed between said piers.
22. A transportation system consisting of shore connections having a sub water line chamber, a tunnel bed reinforced through-

out its length, and a tunnel construction united with said bed and connected in water tight union with said sub water line chamber.

- 5 23. A transportation system including wharf structures on opposite sides of a water way having water proof chambers above and below the water line and a wharf floor, the latter being connected with surface 10 roadways, a tunnel bed having piers at pre-determined distances apart and reinforced intermediate said piers, a tunnel construction carried by said bed and united with said piers and the reinforced construction 15 therebetween to form a unit of structure, said tunnel being connected in water proof union with one of the water proof chambers of the shore connections.
24. A transportation system consisting of 20 shore connections having sub water line chambers provided with crossover tracks, subway lines in water proof union with said chambers and having tracks in communication with the crossover tracks, and a tunnel 25 line in water proof union with said chambers.

25. A transportation system consisting of shore terminals in water proof union with a tunnel, the tunnel having cords extending therethrough and anchored to said terminals. 30

26. A transportation system consisting of shore terminals in water proof union with a bridging construction embedded in concrete and water proofing material, and ballasted into union with the bed of a water-way. 35

27. A transportation system consisting of shore terminals built of structural metal embedded in a layer of waterproof material 40 and concrete, and a tunnel of structural metal embedded in a layer of waterproof material and concrete; the tunnel layer of waterproof being in union with the layer of waterproof of the shore terminals and 45 the structural metal of the tunnel being connected with the structural metal of the shore terminals.
